UNITED STATES PATENT OFFICE.

HARRIS TABOR, OF ELIZABETH, NEW JERSEY, ASSIGNOR TO THE TABOR MANUFACTURING COMPANY, OF NEW YORK, N. Y.

MOLDING-MACHINE.

SPECIFICATION forming part of Letters Patent No. 448,596, dated March 17, 1891.

Application filed December 15, 1890. Serial No. 374,830. (No model.)

To all whom it may concern:

Be it known that I, HARRIS TABOR, of Elizabeth, Union county, New Jersey, have invented certain new and useful Improvements in Metal-Founding Machines, of which the following is a specification.

This invention pertains to that class of molding-presses employed by the metal-founder in compacting the sand in his molds, and the improvements will be readily understood from the following description, taken in connection with the accompanying drawings, in which—

Figure 1 is a side elevation of a metal-founding machine exemplifying my improvements, this view showing the machine as in open position and having on it the half-flask and sand-box ready to be filled with sand; Fig. 2, a front elevation of the machine, shown partly in vertical section, in the plane of line *a*; Fig. 3, a front elevation similar to Fig. 2, but without any parts appearing in section; Fig. 4, a side elevation, similar to Fig. 1, showing, however, only what may be called the "head" of the machine, this view showing the parts as they would be when the pattern was withdrawn from the mold; Fig. 5, a vertical section of the head of the machine in the plane of line *b*; and Fig. 6, a plan of the head of the machine without stripping-plate or flask, and showing portions broken away to more clearly illustrate the relation of parts.

In following the literal description reference may be most conveniently had to Figs. 1 and 2, reference being had to the other figures in exceptional cases.

Referring to the drawings, 1 indicates a cylinder adapted to produce the ramming power by the use of air or water or steam, my preference, however, being steam; 2, the piston thereof; 3, the inlet to the cylinder for steam or other medium employed, this inlet being below the piston, and it being understood that this inlet will be provided with a suitable valve, by means of which the steam may be admitted to or allowed to exhaust from the cylinder, according as it is desired that the piston rise or fall; 4, the piston-rod, projecting from the piston up out of the cylinder and through a guide in the upper cyl-

inder-head, this piston-rod being of large size and great stiffness, as in the preferred design this piston-rod furnishes the sole guide for the lower member of the press; 5, a plate secured to the upper end of the piston-rod; 6, an open-topped box of which the plate forms the bottom, this box forming what I will call the "head" of the press, this head supporting the pattern and flask, &c., and by its upward movement compressing the sand against an opposing press member or follower above the flask; 7, gaps in two opposite side walls of the box or head to permit of the vertical play of parts which have vertical movement independent of the head; 8, a rectangular frame resting upon or secured to the top of the box, this frame being intended to have secured to it the usual pattern employed in machines of this general class, it being usual, in such molding-presses, to arrange the pattern for attachment to the pattern-carrying element of the press, this frame being hereinafter termed the "pattern-frame;" 9, spurs projecting a short distance upward from the pattern-frame; 10, a rectangular frame resting on these spurs, this frame being intended to have secured to it or formed with it the usual stripping-plate, the preference, however, being that the frame be treated as a part of the machine and adapted to have attached to it such stripping-plates as the work in hand calls for, this frame being hereinafter termed the "stripping-plate" frame; 11, vertical guide-sockets formed upon each side of the head or box 6, these sockets being closed at their lower ends, as seen in Fig. 5; 12, guide-stems attached to the stripping-plate frame and projecting downwardly therefrom into the guide-sockets, as best seen in Fig. 4; 13, air-ports leading outwardly from the guide-sockets near their lower ends, but at such height that the guide-stems will reach down past the air-ports when the stripper-plate frame rests upon the spurs 9; 14, the usual stripper-plate resting upon and preferably attached to the stripper-plate frame; 15, the usual contour-hole in the stripping-plate, this hole being of such form as to closely fit around the pattern to which it belongs; 16, the half-flask resting, as usual, on the strip-

ping-plate; 17, the usual cross-bars in the half-flask; 18, the usual sand-box set above the half-flask and designed to contain extra sand, which it is the duty of the press to transfer compactly into the half-flask; 19, cross-bars in the sand-box, disposed directly over the cross-bars in the half-flask and having a thickness in excess of the bars of the half-flask; 20, the top cross-beam of the press, forming the 50 opposing agent against which the rising and falling head exerts its pressure; 21, strain-rods for supporting the top cross-beam, these rods being pivoted at the base of the machine, so that the top part of the press can be swung 55 back out of the way; 22, the top rammer or follower attached to the cross-beam and designed to press upon the sand in the sand-box and compact the sand in the half-flask, this follower being merely a rectangular block of 60 a size to enter the sand-box, the follower being, if desired, a permanent part of the press, but preferably a separable part, changeable to suit various sizes of flasks in hand; 23, grooves in the lower surface of the follower of 65 a width and depth adapting the follower to pass down through the sand-box to the level of the top of the half-flask, the cross-bars of the sand-box entering the grooves of the follower; 24, a pipe or channel extending through 70 the piston and piston-rod from the lower portion of the cylinder to within the press-head; 25, a closed cavity extending around within the body of the pattern-frame 8; 26, a pipe placing this cavity in communication with the 75 pipe 24, whereby steam from the cylinder is always in free communication with the cavity, thus keeping the pattern-frame, and such pattern as may be on the pattern-frame, warm, the warming of the pattern being found to be 80 a decided advantage in enabling the pattern to be readily withdrawn from the compacted sand of the mold; 27, a pair of hangers secured to the stripping-plate frame 10, and projecting downwardly therefrom outside the 85 pattern-frame 8, the bases of these hangers projecting somewhat into the head through the gaps 7 in the side walls of the head or box; 28, a plate resting on the inward projections of the hangers and becoming thus disposed normally near the floor of the box or 90 head and some distance below the pattern-frame 8; 29, a rock-shaft supported in bearings on the upper head of the cylinder and extending across the front of the machine; 95 30, a lever-toe at each end of the rock-shaft, the movement of the rock-shaft bringing these toes either vertically over the rock-shaft or forward from such position, as desired; 31, levers, one at each side of the head or box, 100 the rear ends of these levers being pivoted to the box while the free forward ends are at liberty to sweep in an arc passing through the point of occupancy of the lever-toes 30 when those toes are in their upward position; 32, links pivoted at their upper ends to the hangers 105 27, and at their lower ends to intermediate

portions of the levers 31; 33, a foot-lever on the rock-shaft; 34, a hand-lever, or two of them, on the rock-shaft.

Referring to Fig. 2, let it be assumed that 70 the pattern-frame 8 carries the usual pattern, that portion of the pattern structure which forms the pattern proper projecting up through the contour hole 15 in the stripping-plate, the pattern proper thus occupying the 75 usual position above the stripping-plate and within the half-flask. The half-flask and sand-box will be filled with sand, as usual, and the follower brought into position over the sand-box. Steam will now be admitted under the 80 piston, and the entire lower press member, carried by the upper end of the piston-rod, will rise and the follower will forcibly enter the sand-box and press the sand out of the same and into the half-flask, compressing it tightly in 85 the half-flask and around the pattern and on top of the stripping-plate. This finishes the pressing operation and the half-mold is completed, but still in the press and with the pattern still in the mold. If now the steam be let 90 out of the cylinder, then the parts which have risen will again descend and the press will be opened and the follower may be swung rearwardly out of the way; but this leaves the completed half-mold still in the press and the 95 pattern still in the mold, for there has been no withdrawal of the pattern. What is wanted is that the flask and stripping-plate shall be held up while the pattern is withdrawn downwardly. The want is often provided for in molding-presses; but I provide for it by means of a peculiar system. When the head, &c., is in its upward position and the ramming completed, the levers 31 (see Fig. 1) will have risen also, rising bodily and 100 not turning on their pivots. The parts will have risen so far that the rock-shaft may be turned so that lever-toes 30 are beneath the free ends of the levers 31. Now under these conditions when the steam is allowed 105 to exhaust from the cylinder the head will descend, as before described, and the pattern-frame and attached pattern will descend with it to the normal position. As the head descends, so also will the levers 31 descend, the 110 pivots of those levers being upon the head; but the forward ends of the levers cannot descend, being supported by the lever-toes. The consequence is that the lever-toes form new fulcrums for the levers 31, and that as 115 the head descends the forward ends of the levers do not descend, but the rear ends of the levers make the full descent, intermediate portions of the levers descending through less distance and at lower speed. The links connect the intermediate portions of the levers with the stripping-plate frame, and the result is that while the head or box and the pattern and the rear pivots of the levers have made the full descent the stripping-plate frame has 120 made only a partial descent, as shown in Fig. 4. The stripping-plate and mold have de- 125

scended somewhat, but the main head and pattern have made a full descent; consequently the pattern has been withdrawn downwardly through the stripping-plate, 5 leaving the half-mold ready for removal from the press. The stripping-plate frame normally rests on the spurs 9, made spur-like or nearly sharp, so that sand will not be apt to lodge upon them and prevent the 10 stripper-plate frame resting fairly upon them, the resting of the stripping-plate frame on these spurs controlling the proper normal relationship of stripping-plate to pattern. As the head moves down in advance of the stripping-plate frame the spurs leave the stripping-plate frame, which becomes supported entirely by the links, and the guide-studs in 15 the sockets insure the proper parallel movement and position of the parts. When the 20 flask has been removed, then the rock-shaft is tripped by hand or foot, thus removing the lever-toes from under the levers 31, whereupon the stripping-plate frame is at liberty to drop and rest again upon the spurs, thus 25 putting the stripping-plate again in normal relationship to the pattern ready for the placing of a new half-flask. When the rock-shaft is tripped, then the stripping-plate frame might come down upon the spurs with serious 30 shock. This I obviate by causing the lower ends of the guide-studs to pass the air-holes 13 in the guide-sockets, thus penning up air in the guide-sockets and producing a cushion to relieve the shock, the penned-up air slowly 35 leaking past the guide-studs and allowing the stripping-plate frame to come fairly down upon the spurs.

It is well understood that the stripping-plate may deal with the exterior of a pattern, 40 but that if a pattern has a ring-like form or has interior surfaces which require stripping, then recourse must be had to independent patches of stripping-plate, which must be supported from below the pattern, these independent stripping-patches being termed 45 "stools." Should any of the usual stools be required they may be supported on the stool-plate 28. (Best shown in Fig. 2.) This plate is supported by the lower ends of the hangers, 50 and thus forms a portion of the stripping-plate structure and partakes of its movements. The stool-patches will be carried, as usual, on studs extending upward from the stool-plate 28, the patches being level with 55 the stripping-plate, as usual. Where stools are not to be provided for there will of course be no necessity for the stool-plate 28 or for the arrangement of hangers and gaps for its support, and in such cases the box-like structure 60 6, which I have provided to give space under the pattern-frame for the movement of the stool-plate, will not be required, and the pattern-frame may rest directly on the table or plate 5.

65 The rock-shaft arrangement is an efficient device for bringing the obstructing toes un-

der the levers; but any other suitable arrangement of these toes whereby they obstruct or do not obstruct the descent of the free ends of the levers may be employed. 70

Instead of employing the pressure-cylinder as a means for forcibly raising the head, any of the mechanical devices usually employed in metal-founding processes may be substituted. 75

I claim as my invention—

1. In metal-founding apparatus, the combination, substantially as set forth, with a press and pattern support, of a stripping-plate supported by the pattern-support, and mechanism for moving the pattern-support and stripping-plate simultaneously, but at differing 80 velocities. 85

2. In metal-founding apparatus, the combination, substantially as set forth, with a press and a pattern-supporting press-head moved thereby, of a stripping-plate supported by the press-head, a lever pivoted to the press-head, a link connecting the lever with the stripping-plate, and a movable toe to obstruct the 90 movement of one end of the lever. 95

3. In metal-founding apparatus, the combination, substantially as set forth, of a box-like press-head, a pattern-frame carried thereby, a stripping-plate frame carried by the press-head, a stool-plate within the press-head, hangers connecting the stool-plate with the stripping-plate frame, a follower, and means for independently moving the pattern-frame and stripping-plate frame as the press opens. 100

4. In metal-founding apparatus, the combination, substantially as set forth, of a press-head arranged to support a pattern and provided with guide-sockets, a stripping-plate frame provided with guide-studs engaging 105 said guide-sockets, a follower, and means for pressing said press-head and follower toward each other. 110

5. In metal-founding apparatus, the combination, substantially as set forth, of a press-head provided with guide-sockets having air-ports, a stripping-plate frame having guide-studs engaging said guide-sockets, a follower, and means for pressing said press-head and follower toward each other. 115

6. In metal-founding apparatus, the combination, substantially as set forth, with a press-head, a follower, and means for pressing them toward each other, of a pattern-frame supported by the press-head and provided with upwardly-projecting spurs, and a stripping-plate supported by said spurs. 120

7. In metal-founding apparatus, the combination, substantially as set forth, of a press, a pattern-frame having a closed cavity, and a 125 steam-pipe communicating with such cavity.

8. In metal-founding apparatus, the combination, substantially as set forth, of a steam-cylinder, a piston therein, a piston-rod having through it a passage communicating with 130 the steam-space of the cylinder, a pattern-frame carried by the piston-rod and having

a closed cavity communicating with the passage in the piston-rod, and a follower.
9. In metal-founding apparatus, the combination, substantially as set forth, of a press-head, a half-flask thereon provided with a cross-bar, a sand-box disposed over the half-flask and provided with a cross-bar over and of greater thickness than the cross-bar of the

half-flask, a follower arranged to enter the sand-box, and means for pressing the follower to and press-head toward each other.

HARRIS TABOR.
